RIBBON BAR

James A. Leonard, Jr., Chicago, Ill., assignor to F. H. Noble and Company, Chicago, Ill., a corporation of Illinois:

Application July 10, 1953, Serial No. 367,254

3 Claims. (Cl. 40—1.5)

This invention relates to a novel and improved ribbon bar for use on presentation attachments, badges, and the like.

In mounting ribbons, badges, and awards of various types, a suspending device known as a ribbon bar is commonly employed and comprises generally a metal attachment having means for securing the same to a ribbon or the like and also carrying a pin for affixing the entire article to the garment of the wearer. In the case of a badge or ribbon, the ribbon bar is usually sewed or otherwise connected to the upper end portion of an elongated ribbon or badge. In the case of a so-called presentation attachment, the ribbon bar is attached to the upper end portion of a somewhat shorter ribbon and a ring is provided at the lower end portion of the ribbon for mounting any suitable medal, charm, or other award.

Heretofore in the art, ribbon bars have frequently been of a type requiring the ribbon to be attached by sewing with the stitches extending through the fabric of the ribbon and also through apertures provided in the ribbon bar. Moreover, the attaching pin is often soldered to the back of the ribbon bar thereby increasing the cost of the manufacturing operation. In other instances, ribbon bars have been made in two or more parts with the ribbon clamped therebetween.

As will hereinafter appear, my invention provides a simple and inexpensive one-piece ribbon bar construction which completely eliminates the necessity of sewing in order to attach the ribbon and also eliminates the use of soldering to mount the attaching pin on the bar. Moreover, the invention provides special concealed retaining means on the ribbon bar for insuring proper display positioning of the ribbon relative to the bar.

Accordingly, a primary object of the invention is to provide a novel ribbon bar having substantial advantages over the constructions heretofore used in the art.

A further object of the invention is to provide a novel and inexpensive one-piece ribbon bar construction characterized by a high degree of simplicity in manufacture and use.

Another object of the invention is to provide a novel and improved ribbon bar construction which does not require soldering in its manufacture and which can be attached to a ribbon in a simple fashion without the use of sewing.

An additional object of the invention is to provide a novel ribbon bar and combination thereof with a ribbon characterized by special retaining means which is concealed from normal view and which insures proper display positioning of the ribbon relative to the ribbon bar.

Other objects and advantages of the invention will be evident from the subsequent detailed description taken in conjunction with the accompanying drawing, wherein:

Fig. 1 is a front elevational view of a presentation attachment including a ribbon bar embodying the principles of my invention;

Fig. 2 is a rear elevational view on an enlarged scale of the article seen in Fig. 1;

2

Fig. 3 is a transverse sectional view on a further enlarged scale as taken along the line 3—3 of Fig. 2;

Fig. 4 is a plan view of metal blank constituting one stage in the manufacture of the ribbon bar;

Fig. 5 is a perspective view showing the metal blank of Fig. 4 as bent during the step of attaching the ribbon bar to a ribbon; and

Figs. 6 to 8 are side elevational views showing the successive steps involved in attaching the ribbon bar to a ribbon.

10 Referring first to Figs. 1 and 2, the invention is illustrated herein in connection with a presentation attachment comprising a ribbon 10 with a ribbon ring 11 at the bottom thereof and a ribbon bar 12 at the top thereof. The ribbon 10 in this case is of fabric having a plurality of different colored stripes 13. A medal, shown fragmentarily at 14, is suspended from the ribbon ring 11 in the usual manner.

Referring next to Figs. 3—5, the ribbon bar 12 is formed by stamping out from a bendable metal, such as brass, an elongated one-piece blank designated generally at 15 in Fig. 4. The strip or blank 15 is notched at 16 to permit folding or bending along the dotted vertical line 17 in Fig. 4 thereby providing a front strip portion 18 and an integrally connected rear strip portion 19. The front strip portion 18 is formed with an end tab or tongue 20 foldable along the dotted line 21 and having an outwardly punched tang or barb 22. A similar tang or barb 23 is punched out adjacent the opposite end of the strip portion 18. Depending angularly from the front strip portion 18 adjacent the opposite ends thereof are a pair of bendable fingers or retainer tabs 24 for the purpose described hereinafter.

The rear strip portion 19, which is adapted to be folded into substantially parallel clamping relation with the front strip portion 18, is provided with a pair of openings or apertures 25 and 26 for receiving the tangs 22 and 23, respectively, when the blank 15 is folded. The strip portion 19 also carries a pair of apertured flanges 27 projecting outwardly therefrom in parallel relation for pivotally 30 mounting a pin catch 28, the pin 28 having an eyelet 29 at one end which is fitted between the flanges 27 and secured thereto by a pivot or rivet member 30. The pin 28 is adapted to be retained in closed position by means of a downwardly curved hook portion 31 on the rear strip portion 19 which coacts with the pointed end of the pin 28.

Referring now to Figs. 3 and 6—8, the method of assembling the ribbon bar on a ribbon or the like will now be described. The ribbon 13 in this instance comprises a length of ribbon fabric which is threaded through the ribbon ring 11 and the end portions of the ribbon are then brought together in substantial side-by-side alignment, as indicated at 32 and 33. With the metal blank comprising the ribbon bar partially folded into its Fig. 5 condition, the aligned ends of the ribbon layers 32 and 33 are first inserted downwardly between the strip portions 18 and 19 in the manner indicated in full lines in Fig. 6. The front and rear strips 18 and 19 are then pressed together and the tab 20 on the front strip portion 18 is folded over against the corresponding end of the rear strip portion 19 thereby securely clamping the superimposed ends of the ribbon layers 32 and 33 between the strip portions 18 and 19 as clearly shown in Fig. 3. Also, as best seen in Fig. 3, this clamping action causes the tangs 22 and 23 to penetrate the double thickness of ribbon fabric so that the ribbon is securely fastened to the ribbon bar. The tang 22 extends forwardly through the aperture 26 and first pierces the ribbon layer 32, whereas the tang 23 projects rearwardly toward the aperture 25 and penetrates first through the ribbon layer 33.

70 Thereafter, the double thickness ribbon fabric is swung downwardly over the front of the ribbon bar, as indicated

by the arrow in Fig. 6. The angular fingers 24 are then bent upwardly and inwardly to overlie the respective side edges of the innermost ribbon layer 33, in the manner shown in Fig. 7, thereby clamping the edges of the ribbon layer 33 against the front strip portion 18. Thus, the folded retaining fingers 24 insure that the ribbon 10 will hang in proper display position at the front side of the ribbon bar, and at the same time the retaining fingers 24 are concealed from normal front view by the overlying front ribbon layer 32 when the article is completely assembled as in Fig. 8.

It will be seen from the foregoing that the invention provides a very simple, inexpensive, and essentially one-piece ribbon bar construction which can readily be manufactured and assembled by low cost methods. Moreover, the construction is such that the pin catch can readily be mounted without soldering or like operations. In addition, no sewing whatsoever is necessary to attach the bar to a ribbon, the ribbon being clamped between portions of the ribbon bar structure and being further secured by pointed elements penetrating into the ribbon material. An important novel feature of the invention resides in the provision of the foldable fingers or tabs which serve to maintain the ribbon in proper display relation at the front side of the ribbon bar while being substantially concealed from normal view by the ribbon material.

Although the invention has been described with reference to a particular structural embodiment, it will be understood that various modifications and equivalent structures may be employed without departing from the scope of the invention as defined in the appended claims.

I claim:

1. In a ribbon bar comprising coacting front and rear clamping strips adapted to be clamped together on opposite sides of a double thickness of ribbon material with both ribbon layers extending forwardly and downwardly in display position over the front clamping strip, the improvement which comprises a pair of foldable finger elements depending angularly and outwardly from the bottom of said front strip whereby to project beyond the vertical side edges of the superimposed ribbon layers, said finger elements being foldable upwardly and inwardly for clamping the side edges of the innermost ribbon layer against said front strip whereby to retain the ribbon in proper display relation at the front of the ribbon bar, and said finger elements when so folded being adapted to be concealed from normal view by the outermost ribbon layer.

2. In combination, a ribbon bar comprising coacting

front and rear clamping strips, a ribbon comprising a double layer of ribbon material with the ends thereof clamped between said strips, said ribbon extending forwardly and downwardly over the front clamping strip in display relation, and a pair of retaining fingers extending from the opposite ends of said front clamping strip and folded upwardly and inwardly over the innermost layer of ribbon material for clamping the side edges of said innermost layer against said front strip whereby to retain the ribbon in proper depending display relation with respect to the ribbon bar, the outermost ribbon layer overlying said folded fingers for concealing the same from normal view.

3. In combination, a ribbon bar comprising an elongated strip folded centrally to provide a pair of coacting front and rear clamping portions, a double thickness of ribbon material interposed between said clamping portions and extending over and downwardly in display relation in front of said front clamping portion, a foldable tab at the free end of said front clamping portion adapted to be folded around and against the corresponding free end of said rear clamping portion, pointed tang means projecting from at least one of said clamping portions for penetrating the ribbon material, the other of said clamping portions being provided with aperture means alignable with said tang means for facilitating penetration of the ribbon material by said tang means, means on said rear clamping portion for mounting an attaching pin for fastening the device on a garment or the like, and a pair of foldable fingers depending angularly and outwardly from said front clamping portion adjacent the opposite ends thereof, said fingers being folded upwardly and inwardly against the sides of the innermost thickness of ribbon material for pressing the same against said front clamping portion whereby to retain the ribbon material in proper display relation, the outermost thickness of ribbon material overlying said folded fingers for concealing the same from normal view.
